DOOR KNOB

Fred J. Russell, 8635 Otis St., South Gate, Calif.

Filed Mar. 31, 1964, Ser. No. 79,279

Term of patent 14 years

(Cl. D50—3)

FIG. 1.

FIG. 2.

FIG. 3.

FIG. 5.

FIG. 4.

FIGURE 1 is a side elevational view of a door knob showing my new design;

FIGURE 2 is a front elevational view;

FIGURE 3 is a rear elevational view;

FIGURE 4 is a fragmentary cross sectional view of the wall on the line 4—4 of FIGURE 1 showing the character and depth of configurations on the exterior; and

FIG. 5 is a longitudinal sectional view of FIG. 1.

I claim:

The ornamental design for a door knob, as shown.
